UNITED STATES PATENT OFFICE.

ISIDOR J. KUSEL, OF CHICAGO, ILLINOIS.

DESIGN FOR A COIN BANK.

Application filed June 10, 1922. Serial No. 2,611. Term of patent 3½ years.

To all whom it may concern:

Be it known that I, ISIDOR J. KUSEL, a citizen of the United States, residing at Chicago, in the county of Cook and State of Illinois, have invented a new, original, and ornamental Design for Coin Banks, of which the following is a specification, reference being had to the accompanying drawings, forming part thereof.

Fig. 1 is a plan view of a coin bank embodying my novel design;

Fig. 2 is a front elevation of the same.

I claim:

The ornamental design for a coin bank, as shown.

ISIDOR J. KUSEL.
